UNITED STATES PATENT OFFICE.

CECIL HAMELIN TAYLOR AND BOUDEWIJN B. NEUTEBOOM, OF DETROIT, MICHIGAN.

AUTOMOBILE.

1,209,228.

Specification of Letters Patent.

Patented Dec. 19, 1916.

Application filed April 5, 1912. Serial No. 688,782.

To all whom it may concern:

Be it known that we, CECIL HAMELIN TAYLOR, a citizen of the United States, and BOUDEWIJN B. NEUTEBOOM, a subject of the Queen of the Netherlands, residing at Detroit, county of Wayne, State of Michigan, have invented a certain new and useful Improvement in Automobiles, and declare the following to be a full, clear, and exact description of the same, such as will enable others skilled in the art to which it pertains to make and use the same, reference being had to the accompanying drawings, which form a part of this specification.

15 Our invention relates to automobiles and an object of our improvements is to provide an improved construction of the driving gear by which the parts may be readily assembled and taken apart.

20 In the accompanying drawings:—Figure 1, is a plan view partly in section of the rear axle and adjacent parts showing the counter shaft and its housing in the process of being removed or placed. Fig. 2, is a plan view mostly in section of a portion of the counter shaft and its casing and the rear axle, and the method of joining the same and assembling the parts. Fig. 3, is a detail view showing a part of one of the rear 25 wheels with the axle, counter shaft, and casing in place. Fig. 4, is a detail view broken away showing the first step in disassembling the parts. Fig. 5, is a side view looking from the left of Fig. 2. Fig. 6, is a detail plan view illustrating the connection of the supporting arm L with the rear axle.

A, is a rear axle, and B B represents the wheels adapted to turn on the end of the axle A.

30 C, is a cylindrical casing having one end closed by a web which is secured by bolts q, q, q¹, q¹, to the wheel B.

D, is an internally toothed gear wheel secured by bolts q q to the wheel and the web of the casing C.

E, is the usual two-part counter shaft, its parts being joined at the center by the equalizing gear in the usual way.

35 F J is a casing for the counter shaft E. Said casing is composed of the casing J for the equalizing gear and the adjacent driving mechanism, and tubes F, F extending laterally from the casing J. The tubes F, F are expanded at their outer ends, as indicated at f f and the outer ends of the

parts of the counter shaft E rest in bearings in the expanded portion of these tubes.

H, is a spider closing the inner ends of the cylindrical casing C and secured to the shaft A.

G, is a sleeve adapted to fit upon the expanded portions of the casing F, and to fit within an opening h in the spider H. The sleeve G is provided with a flange g which is secured by bolts d to the spider H. The 65 construction is the same at each end of the casing so that only one end need be described.

J, is a casing for the equalizing gear and the inner end of the transmission shaft K. 70 The casing J forms the center portion of the casing F.

S, indicates the usual bevel-gear wheels on the adjacent inner ends of the parts of the shaft E.

75 R, is a revolute housing sleeved upon the adjacent ends of the parts of the shaft E.

r, is a planetary gear wheel adapted to turn on a spindle extending radially inward from the housing R, and engaging the bevel-gear wheels S. The left-hand side of the housing R is faced off and is provided with keys I, I.

P, is a bevel-gear wheel having radial key seats in its face adjacent to the housing R, 85 in which engage the keys I, I, which are in sockets in the faced off portion of the housing R.

z, shown in dotted lines in Fig. 2, represents a rivet by which the bevel-gear wheel P is secured in position so that the keys I, I engage in the radial key ways in the face of said gear wheel.

O, is a bevel-gear wheel on the inner end of the shaft K, its teeth engaging the teeth 95 of the gear wheel P.

j, j, are lugs upon the left hand end of the casing J.

L, is an arm secured by a key m (Figs. 5 and 6) to the axle A. Said arm being provided with a split sleeve extending over said axle, which sleeve is also provided with lugs N adapted to be engaged by bolts n n to clamp the sleeve upon the axle and secure the arm L firmly in place. The arm L at 105 its end remote from the axle A is provided with a fork having the two branches M, M, the opening between these branches extends horizontally and opens toward the rear of the vehicle or away from the axle A.

T, T, are bolts by which the branches M M of the fork arm L are secured to the lugs j j on the casing J, said lugs coming against the side of the fork.

5 It will be observed that by this construction the arm L may be adjusted longitudinally of the axle A and the casing F J being secured to the outer end and against the side of the arm L is accurately adjusted to place 10 and firmly secured in its adjusted position.

When it is desired to remove the shaft E with its casing the sleeves G are loosened from the spider H and drawn back upon the smaller portion of the casing F, as indicated 15 in Fig. 4, or at the right of Fig. 1. A wheel B is loosened and drawn partly off from the axle A. The bolts T are then loosened separating the casing J from the arm L and the casing F with its inclosed shaft is moved 20 endwise to free one end from the spider H, which end is then moved horizontally, as illustrated in Fig. 1, until it is free from said spider when it may be again moved in the direction of its length to free the other 25 end from the spider and adjacent parts and remove the casing F J and its contained parts.

It will be observed that in the above construction there are two cylindrical bearings 30 at the ends of the counter shaft having their axis parallel to the axis of the axle, and there is one bearing toward the center of said counter shaft, the contiguous surfaces of which are in a plane at right angles 35 to the axis of the axle. The arm L is also adjustable longitudinally of the axle A. Thus the counter shaft is adjustable in the direction of the axle A and accurate milled surfaces are not required.

40 The construction by which the bevel gear wheel P is secured in place is simple and strong and easily adjusted.

What we claim is:—

1. In an automobile, an axle, a counter 45 shaft, a casing for said counter shaft, wheels adapted to turn upon the ends of said axle, toothed gear wheels secured to said wheels concentric with said axle, said shaft being provided with pinions adapted to engage 50 said toothed gear wheels, spiders toward the end of said axle mounted thereon, apertures in said spiders, sleeves upon the ends of said casing adapted to be secured to said spider 55 coaxial with said aperture, said aperture being of greater diameter than said casing.

2. In a vehicle, the combination of an axle, a shaft casing having a bracket secured to said axle and secured to said casing at two points at a distance from each other and approximately in the same vertical plane.

3. In an automobile, an axle, an arm secured to said axle and having a fork at its outer end, a counter shaft, a casing for said counter shaft, said fork being adapted to receive 65 said casing, said casing being provided

with lugs adapted to be secured to the side of the fork of said arm.

4. In an automobile, an axle, an arm secured to said axle and having a fork at its outer end, a counter shaft, a casing for said counter shaft, said fork being adapted to receive 70 said casing, said casing being provided with lugs adapted to be secured to the side of the fork of said arm, said arm being keyed to said axle so as to be adjustable longitudinally thereof.

5. In an automobile, an axle, an arm secured to said axle and having a fork at its outer end, a counter shaft, a casing for said counter shaft, said fork being adapted to receive 75 said casing, said casing being provided with lugs adapted to be secured to the side of the fork of said arm, wheels adapted to turn upon the ends of said axle, internal toothed gear wheels secured to said wheels concentric with said axle, said shaft being provided with pinions adapted to engage the teeth of 80 said internal toothed gear wheels.

6. In an automobile, an axle, an arm immovably secured to said axle and having a 90 fork at its outer end, a counter shaft, a casing for said counter shaft, said fork being adapted to receive said casing, said casing being provided with lugs adapted to be secured to the side of the fork of said arm, wheels adapted to turn upon the ends of said axle, internal toothed gear wheels secured to 95 said wheels concentric with said axle, said shaft being provided with pinions adapted to engage said internal toothed gear wheels, spiders toward the end of said axle mounted thereon, said casing being mounted in said 100 spiders.

7. In an automobile, an axle, an arm secured to said axle and having a fork at 105 its outer end, a counter shaft, a casing for said counter shaft, said fork being adapted to receive said casing, said casing being provided with lugs adapted to be secured to the side of the fork of said arm, wheels 110 adapted to turn upon the ends of said axle, internal toothed gear wheels secured to said wheels concentric with said axle, said shaft being provided with pinions adapted to engage 115 said internal toothed gear wheels, spiders toward the end of said axle mounted thereon, apertures in said spiders, sleeves upon the ends of said casing adapted to fit into said apertures and to be secured therein, and to be removed therefrom to permit 120 the passage of said pinions through said apertures.

8. The combination of the housing R, a key fixed in one side of said housing, a bevel gear wheel having radial slots in its face, 125 said wheel being secured to said housing with said keys in said slots.

9. In an automobile, an axle, an arm immovably secured to said axle, a counter shaft, a bearing for said counter shaft re- 130

movably secured to said arm, wheels adapted to turn upon the ends of said axle, internal toothed gear wheels secured to said wheels concentric with said axle said shaft 5 being provided with pinions adapted to engage the teeth of said internal toothed gear wheels.

10. In an automobile, an axle, an arm immovably secured to said axle and having 10 a fork at its outer end, a counter shaft, a casing for said counter shaft, said fork being adapted to receive said casing, said casing being provided with lugs adapted to be secured to the side of the fork of said arm, 15 wheels adapted to turn upon the ends of said axle, toothed gear wheels secured to said wheels concentric with said axle, said shaft being provided with pinions adapted to engage the teeth of said toothed gear 20 wheels.

11. In an automobile, an axle, an arm immovably secured to said axle and having a fork at its outer end, a counter shaft, a casing for said counter shaft, said fork being adapted to receive said casing, said casing being provided with lugs adapted to be secured to the side of the fork of said arm, 25 wheels adapted to turn upon the ends of said axle, toothed gear wheels secured to said wheels concentric with said axle, said shaft being provided with pinions adapted to engage said toothed gear wheels, spiders 30 toward the end of said axle mounted thereon, said casing being mounted in said 35 spiders.

12. In an automobile, an axle, an arm secured to said axle and extending therefrom, a counter shaft, a casing for said counter shaft, said casing being provided 40 with lugs adapted to be secured to the side of said arm, wheels adapted to turn upon the ends of said axle, toothed gear wheels secured to said wheels concentric with said axle, said shaft being provided with pinions 45 adapted to engage said toothed gear wheels,

spiders toward the end of said axle mounted thereon, apertures in said spiders, sleeves upon the ends of said casing adapted to fit into said apertures and be secured therein, and to be removed therefrom to permit the 50 passage of said pinions through said apertures.

13. In an automobile, an axle, a counter shaft, a casing for said counter shaft, wheels adapted to turn upon the ends of said axle, 55 toothed gear wheels secured to said wheels concentric with said axle, said shaft being provided with pinions adapted to engage said toothed gear wheels, spiders toward the end of said axle mounted thereon, apertures in said spiders, sleeves upon the ends of said casing adapted to be secured to said 60 spider coaxial with said apertures.

14. In an automobile, the combination of an axle, a driving wheel on the same, a driving shaft provided with an engagement by which a driving wheel may be actuated, a casing for said shaft, an arm secured to said axle so as to be adapted to be moved horizontally thereon, said arm and casing 70 being provided with vertical engaging surfaces.

15. In an automobile, the combination of an axle, a driving wheel on the same, a driving shaft provided with an engagement by 75 which a driving wheel may be actuated, a casing for said shaft, a part secured to the automobile, said part being provided with a vertical surface, a casing for said shaft, said casing being provided with a vertical 80 surface, said part and said casing being secured together with said vertical surfaces in contact.

In testimony whereof, we sign this specification in the presence of two witnesses.
